ATTORNEY

UNITED STATES PATENT OFFICE

JOHN C. CURTIS, OF CLEVELAND, OHIO, ASSIGNOR TO THE CLEVELAND ROCK DRILL COMPANY, OF CLEVELAND, OHIO, A CORPORATION OF OHIO

STEEL RETAINER ATTACHMENT FOR ROCK DRILLS

Application filed May 29, 1931. Serial No. 540,858.

This invention relates broadly to rock drills but more particularly to steel retainer attachment for rock drills of the hammer type.

5 One object of this invention is to provide a rock drill with a steel retainer adaptable to be readily attached to or detached from the machine.

Another object of this invention is to provide a rock drill with a steel retainer having removable supporting means, thus facilitating the interchangeability as well as reducing the replacement cost of the worn parts.

Another object of this invention is to provide a steel retainer with a positive locking device of the supporting shaft within its housing, eliminating thereby the use of parts which may become loose from the vibration caused by the reciprocation of the hammer.

Other objects and advantages more or less ancillary to the foregoing, and the manner in which the various objects are attained reside in the specific construction and aggroupment of the elements peculiar to this structure, as will become apparent from a more complete examination of this specification, in the claims of which there are assembled certain specific combinations of parts and specific constructions indicative of the scope and spirit of the invention.

In the drawing illustrating a practical application of the invention:

Figure 1 is an elevational view partly in section of the front end of a rock drill having the invention applied thereto.

Figure 2 is a side elevational view partly in section illustrating the locking device of the retainer.

Figure 3 is an end elevational view of the parts shown in Figure 1.

Figure 4 is a cross sectional view taken on the line 4-4 in Figure 1, looking in the direction indicated by the arrows.

Referring to the drawing, in which like symbols designate corresponding parts throughout the several views, there is shown a front head 10, constituting the lower portion of the casing of a percussive rock drill, which is provided with a cylindrical bore 11, terminated by a shoulder 12, for limiting

the penetration of a bushing 13, snugly fitted therein. The bushing 13 is internally shaped to slidably receive the tool, implement or drill steel 14, engageable therein through the medium of the integral shank 15, which is adapted to receive the blows of the hammer piston (not shown) and has its penetration therein limited by the collar 16, disposed thereon at a suitable distance from its end.

55 The housing 10, is formed with a protuberance 17, provided with an aperture 18, transversally disposed therein and partly registering or opening within the bore 11, and is fitted to slidably receive a pin 19, which is formed intermediate its ends with a restricted portion 20, having a concave configuration 21, similar and slightly larger than the front head's bore 11. The ends of the pin 19, are protruding from the protuberance 17, the purpose of which will be explained later.

70 Extending beyond the forward end of the front head 10, there is the retainer 22, provided with a yoke 23, of a smaller internal diameter than the outside diameter of the collar 16 and having two parallel arms 24, which are terminated by an enlarged portion 25, provided with a transversal aperture 26, fitted to rotatably engage upon the protruding ends of the pin 19. Adjacent the enlarged portion 25, the front head is manufactured

75 with two oppositely disposed cylindrical bores 26, in parallel alignment with the axis of the tool and of suitable size to slidably receive the plunger 27, having one end terminated with a V shaped edge 28, adaptable for engagement within the corresponding recesses on detents 29 and 30, formed upon the vertical wall of the enlarged portion 25, of the arms 24. The plunger 27, is urged forwardly or maintained in engagement with its corresponding recess, by the tension of the compression spring 31, disposed intermediate the ends of the bore 26, and plunger 27. The

80 walls of the bores 26, have their front faces 32, manufactured with a rectangular slot 33, of a width somewhat greater than the thickness of the enlarged arms portion 25, and of a sufficient depth to provide for a reliable overlapping wall 34, the purpose of which 85 will be explained hereafter.

When assembling the mechanism, the spring and plunger, 31 and 27 may first be introduced within the bores 26. Subsequently, the retainer 22 may be positioned upon the front head 11, with the aperture 18, in axial alignment with the bores 24, and the enlarged portion 25, rocked under the walls 34, or within the rectangular slots 33, thus permitting the introduction of the pin 19, there-through and bringing the restricted concave portion 20, in alignment with the internal wall of the front head bore 11. Subsequently the bushing 13, may be pressed within its respective bore 11, and consequently within the concaved portion 21, as illustrated in Figure 4, thus preventing the removal of the pin 19, from its bore 18. Should it become necessary to replace the pin 19, the bushing 13, will first have to be removed or pressed out before the removal of the pin can take place.

Whenever it is desired to remove the tool implement or drill steel 14 from the machine, the retainer 20, may be rocked to one side of the collar 16, as illustrated in dot and dash line in Figure 2. In this inoperative position the retainer will be maintained in place by the spring pressed plunger 27, engaged within the recess 30; after another drill steel has been inserted into the machine, the retainer may again be rocked to its initial or operative position. It is obvious that it will require a light force to rock the retainer from one position to the other against the tension of the spring 31. However, such a tension is sufficient to maintain the retainer in its operative position against the vibration caused by the reciprocation of the hammer. The walls 34, overlapping the retainer arms or enlarged portion 25, will prevent any possible distortion or spreading of the retainer arms, when the drill steel collar 16, accidentally hits the yoke 23, or when a steel is removed from a drilled hole.

Although the foregoing description is necessarily of a detailed character, in order to completely set forth the invention, it is to be understood that the specific terminology is not intended to be restrictive or confining and it is to be further understood that various arrangements of parts and modification of structural detail may be resorted to without departing from the scope or spirit of the invention as herein claimed.

65 I claim:

1. A drill retainer comprising in combination a front head, a pin within said front head, having means to prevent its removal therefrom comprising a recess within said pin, a bushing engageable with said head and said recess and capable to slidably receive said drill, and a retainer having arms pivotally engaging said pin.

2. A tool retainer for rock drills comprising in combination, a front head having a

bore, a removable bushing within said bore fitted to slidably receive a tool implement, a pin within said front head maintained therein by its engagement with said bushing, and a retainer having arms pivotally mounted upon said pin. 70

3. A tool retainer for rock drills comprising in combination a front head, a pin within said front head having intermediate its ends a restricted portion, a removable bushing within said front head fitted to slidably receive a tool implement, said bushing extending within said restricted portion to hold said pin within said front head, and a retainer having arms pivotally mounted upon said pin. 75 80

4. A tool retainer for rock drills comprising in combination a front head, a pin within said front head having intermediate its ends a restricted portion, a removable bushing within said front head fitted to slidably receive a tool implement, said bushing extending within said restricted portion to hold said pin within said front head, a retainer having arms pivotally mounted upon said pin, and means integral with said front head for preventing the spreading of said arms. 85 90

5. A tool retainer for rock drills comprising in combination a front head, a pin within said front head having intermediate its ends a restricted portion, a removable bushing within said front head fitted to slidably receive a tool implement, said bushing extending within said restricted portion to hold said pin within said front head, a retainer having arms pivotally mounted upon said pin, and means for preventing the spreading of said arms, said means comprising a slot within said front head, having the wall thereof overlapping said arms. 95 100 105

6. A tool retainer for rock drills comprising in combination a front head, a pin transversely of said front head and maintained therein by its engagement with a bushing removably fitted within said front head, a bore within said bushing capable to slidably receive a tool implement, and a tool retainer pivotally mounted upon the outer end portions of said pin. 110 115

7. A tool retainer for rock drills comprising in combination a front head, an aperture within said front head, a pin within said aperture, a removable bushing within said front head fitted to slidably receive a tool implement, said pin being associated with said bushing to prevent the removal of the former from said aperture, and a retainer having arms pivotally engaging said pin. 120 125

8. A tool retainer for rock drills comprising in combination, a front head, a member transversely disposed within said front head forming a pair of trunnions, a removable bushing within said front head fitted to slidably receive a tool implement, means within said member associated with said bushing 130

to hold said trunnions within said front head, and a tool retainer having arms supported by and pivotally mounted upon said trunnions.

9. A tool retainer for rock drills comprising in combination a front head having trunnions protruding therefrom, a removable bushing within said front head fitted to slidably receive a tool implement, means associated with said bushing for preventing the removal 10 of said trunnions from said front head, and a tool retainer having arms pivotally mounted upon said trunnions.

In testimony whereof I hereunto affix my signature this 28 day of May, 1931.
